SANITARY ATTACHMENT LINING FOR
CONTAINERS

Robert I. Innis, Winthrop, Mass.

Application March 22, 1934, Serial No. 716,818

9 Claims. (Cl. 4—173)

My invention relates to sanitary attachment linings for bath-tubs, wash-basins and like containers, and it has for its object to provide an improved device of the character indicated.

5 It is also an object of this invention to provide a strong, durable and efficient attachment lining of the character indicated which can be folded or otherwise collapsed into a small bundle so that it may be conveniently stored or transported; 10 which may be quickly, and securely fastened in operative position within a bath-tub or other container so that it may be quickly detached and removed after use; which will be of comparatively inexpensive construction, and which, in its best 15 form, will provide an inconspicuous lining having a hard, non-fibrous, sanitary and attractively smooth glossy inner surface.

To these ends I have provided a lining attachment of the character described having the 20 peculiar features of construction and operation set forth in the following description, the several novel features of the invention being separately pointed out and defined in the claims at the close thereof.

25 In the accompanying drawing:—

Figure 1 is a top plan view of a lining for a bath-tub, said lining being constructed in accordance with my invention.

Figure 2 is a longitudinal sectional view of a 30 bath-tub provided with a lining like that of Fig. 1.

Figure 3 is an enlarged sectional view of one end portion of the lining illustrated in Figs. 1 and 2.

Figure 4 is an enlarged section on line 4—4 35 of Fig. 3.

Figure 5 is a detail hereinafter referred to.

The embodiment of my invention herein illustrated is a complete, self contained lining structure for a bath-tub, said structure comprising a 40 vessel-like container of thin flexible sheet material that is indicated generally at 10 and which is of a size and shape to fit and cover the interior of a bath-tub 11, particularly the lower portion thereof. The vessel-like container 10 is 45 constructed with a bottom 12 to fit against the bottom of the tub; with oppositely disposed side walls 13 and 14 to fit against the opposite side walls of the tub, and with oppositely disposed end walls 15 and 16 to fit against the end walls of the tub.

The bottom wall 12 is made, adjacent to the end wall 15, with an outlet aperture 17 that is normally closed by a cover or closure element 18 of thin flexible sheet material adhesively and 55 separably fastened to the top side of wall 12 in position to cover and close the outlet 17. This closure element 18 is made at one side thereof that is farthest from the end wall 15 with an integral tang extension 19 which extends upwardly from said closure element to the upper

portion of end wall 15 where it is cemented or otherwise fastened to the inner side of said wall as at 20.

The outlet 17 in bottom wall 12 is located so that when the lining is in position within the tub 11 said outlet is in register with the usual outlet 21 of the tub.

It is a feature of this invention that the exterior of the vessel-like lining is adhesively engaged with the surface of the tub so that it will 10 be maintained in extended vessel-like shape while in use. This engagement may be established by the employment in any suitable manner of an adhesive or cement.

In the best form of my invention however, I 15 provide a plurality of adhesive plaster patches 22 each of which consists of a small piece of textile fabric 23 having a coating of adhesive 24. In practice I have employed patches 22 made from ordinary surgeon's adhesive plaster comprising a 20 textile fabric body 23 coated upon one side with a waterproof adhesive composition 24 including rubber, pitch, and gums, as usual, and which will adhere strongly to any surface without setting or curing so that it can be quickly and 25 cleanly removed or stripped from said surface when desired.

Each patch 22 is permanently mounted upon the inside of the vessel-like lining 10 opposite, or in register with, an aperture 25 formed in 30 the lining.

Each aperture 25 is of non-angular, or circular, shape and is located within the top marginal portion of the lining adjacent to the chime or upper edge thereof. The several apertures 25 35 are located at intervals throughout the circuit of the lining and as will be clear, the adhesive layer of each patch is exposed upon the exterior of the lining by its aperture 25. The area of the aperture 25 is substantially less than the 40 area of that portion of the patch which is adhesively engaged with the wall of the lining so that the latter portion materially reinforces the lining material immediately adjacent to and surrounding the aperture.

45 These exposed portions of adhesive material may adhere to other portions of the lining while the latter is collapsed in the form of a bundle or package while in storage or transit but may be readily disengaged when the lining is opened 50 up for use.

When the lining is to be used it is opened and placed within the tub so that its bottom rests on the bottom of the tub and its upright walls are 55 against the walls of the tub. Then by applying finger pressure to the middle of each patch the adhesive of the latter is shoved into its aperture 25 and against the proximate wall of the tub to which it adheres.

60 After using the tube with the lining in posi-

- tion therein the bather pulls upwardly upon the tang extension 19 and strips the closure element 18 off from the bottom 12 whereupon the contents of the tub and lining discharge by gravity 5 through the outlets 17 and 21 after which the lining is stripped from the walls of the tub and removed.
- The embodiment of my invention herein illustrated has its end wall 16 constructed at its top 10 with an apron extension 26 made near its extremity with apertures 27 and provided with patches 28 attached to the top surface of the extension, each opposite one of said apertures. By means of these patches 28 the upper end 15 of the extension 26 is adhesively attached to the top of the tub so that the extension 26 will serve to hold the end wall 16 against being displaced downwardly through movement of the bather's body against the same.
- 20 It is an important feature of my invention that the vessel-like lining attachment herein illustrated, with the exception of the adhesive patches 22 and 28, is made from a thin waterproof sheet cellulose material such as that which is known 25 commercially as "cellophane". This cellulose material is of great tensile strength; it is non-fibrous; it has a desirably hard, smooth glossy surface, and may be colorless and transparent so that it is not conspicuous.
- 30 An advantage to the use of this material is that the lining is not easily displaced through movements of the body of the bather while the latter is within the tub. Another advantage is that after use, and before removal of the lining 35 40 the latter may, if desired, be quickly cleaned by rinsing or flushing so that, if desired, it may be used more than once although low cost of production permits of discarding the same after one use and for sanitary reasons this may be done. Its use will prevent the spread of disease in hotels and other public places where the bath tubs and wash basins are used by many different people.
- 45 My new lining attachment may be produced in various sizes and shapes appropriate to the bathing container in connection with which they are to be used and therefore the invention is not limited to the particular embodiment herein shown.
- 50 Also the vessel-like structure of the attachment may be made from a single piece of sheet material or from two or more pieces fastened together.
- 55 What I claim is:
1. A lining attachment of the class described consisting of a vessel-like structure of thin flexible sheet material adapted to be fitted within a container, said structure comprising normally adhesive waterproof means for adhesively and separately fastening the upper portion thereof to 60 said container.
  2. A lining attachment of the class described consisting of a vessel-like structure of thin flexible cellulose sheet material adapted to be fitted within a container, said structure comprising normally adhesive waterproof means for adhesively and fastening the upper portion thereof to said container.
  3. A lining attachment of the class described consisting of a vessel-like structure of thin flexible sheet material adapted to be fitted within a container, said structure being made adjacent to its top with apertures, and a patch of waterproof and normally adhesive plaster covering each aperture, said patch being adhesively engaged with the inner surface of said lining struc-

ture surrounding its aperture so that its adhesive material is exposed upon the exterior of said structure through said aperture.

4. A lining attachment of the character described constructed in accordance with claim 3 having a bottom wall made with an outlet and also including a closure element of thin flexible sheet material covering said outlet upon the inner side of said bottom wall and adhesively secured to the latter, said element being made with a tang extension by means of which it is manipulated to open said outlet.

5. A lining attachment of the character described constructed in accordance with claim 3 having a bottom wall made with an outlet and also including a closure element of thin flexible sheet material covering said outlet upon the inner side of said bottom wall and adhesively secured to the latter, said element being made with a tang extension by means of which it is manipulated to open said outlet and said tang extension being adhesively fastened at its outer end to the upper portion of said lining.

6. A lining attachment of the character described constructed in accordance with claim 3 and having an end wall formed at its top with an apron extension to overlie the top of the end wall of the container, said apron extension being provided near its free end with means for adhesively engaging the top of the end wall of said container.

7. A lining attachment of the class described consisting of a vessel-like structure of thin flexible sheet cellulose material adapted to be fitted within a bathing container, said structure being made adjacent to its top with apertures, and a separate patch of waterproof normally adhesive plaster covering each aperture that is of greater area than the latter and adhesively engaged with the inner surface of said lining structure surrounding said aperture so that its adhesive material is exposed upon the exterior of the structure through said aperture.

8. A lining attachment of the character described constructed in accordance with claim 7 having a bottom wall made with an outlet and also including a closure element of thin flexible sheet cellulose material covering said outlet upon the inner side of said bottom wall and adhesively secured to the latter, said element being made with a tang extension by means of which it is manipulated to open said outlet; an apron extension at the top of an end wall of said structure adapted to overlie the top of an end wall of said bathing container, said apron extension being formed near its free end with an aperture, and a patch of waterproof adhesive plaster covering said aperture that is of greater area than the latter and adhesively engaged with the top surface of said extension surrounding said aperture so that its adhesive material is exposed upon the under side of the extension through said aperture.

9. A sanitary cover attachment comprising a sheet of thin flexible waterproof sheet material adapted to be fitted against the surface to be covered, said sheet having a hole formed therethrough, and a small patch of adhesive tape larger than said hole whereof one side only is provided with a single coating of waterproof normally adhesive substance, said patch being adhesively affixed to one side of said cover in register with said hole so that the adhesive material of said patch is exposed through the latter.

CERTIFICATE OF CORRECTION.

Patent No. 1,992,008.

February 19, 1935..

ROBERT I. INNIS.

It is hereby certified that error appears in the printed specification of the above numbered patent requiring correction as follows: Page 2, first column, line 58-59, claim 1, for the word "separately" read --separably--; and that the said Letters Patent should be read with this correction therein that the same may conform to the record of the case in the Patent Office.

Signed and sealed this 13th day of May, A. D. 1941.
